UNITED STATES PATENT OFFICE

PAUL LUERTZING, OF VINELAND, NEW JERSEY

DESIGN FOR A DIRECTION FENDER LAMP

Application filed December 27, 1932. Serial No. 46,624. Term of patent 14 years.

To all whom it may concern:

Be it known that PAUL LUERTZING, a citizen of the United States, residing at Vineland, in the county of Cumberland and the State of New Jersey, has invented a new, original, and ornamental Design for a Direction Fender Lamp, of which the following is a specification, reference being had to the accompanying drawing, forming a part thereof.

Figure 1 is a perspective view of a direction fender lamp showing the new design.

Figure 2 is a view in front elevation of the lamp.

Figure 3 is a top plan view thereof.

What is claimed is:

The ornamental design for a direction fender lamp as shown.

PAUL LUERTZING.
